(57) **CLAIM**

I claim the ornamental design for a chainsaw, as shown and described.

DESCRIPTION

The present application also relates to U.S. design patent application Ser. No. 29/499,703, titled “Chan Sprocket Cover”.

FIG. 1 is a right-rear perspective view of the chainsaw; FIG. 2 is a front view of the chainsaw shown in FIG. 1; FIG. 3 is a rear view of the chainsaw shown in FIG. 1; FIG. 4 is a left side of the chainsaw shown in FIG. 1; FIG. 5 is a right side view of the chainsaw shown in FIG. 1; FIG. 6 is a top view of the chainsaw shown in FIG. 1; and, FIG. 7 is a bottom view of the chainsaw shown in FIG. 1. Applicant expressly reserves the right to modify FIGS. 1-7 to include, in line drawing format, any one or all of the features shown (i.e., shown in either dashed-lines or solid lines) in FIGS. 1-7.

The subject matter shown in dashed lines, and any surfaces of the design not shown, including interior surfaces, form no part of the claimed invention.
